UNITED STATES PATENT OFFICE.

BENJAMIN F. BAIN, OF PITTSBURGH, PENNSYLVANIA.

MECHANICAL-TOY BOWLER ANDY CRANE.

1,355,636.

Specification of Letters Patent. Patented Oct. 12, 1920.

Application filed June 30, 1919. Serial No. 307,624.

To all whom it may concern:

Be it known that I, BENJAMIN F. BAIN, a resident of Pittsburgh, in the county of Allegheny and State of Pennsylvania, have 5 invented a new and useful Improvement in Mechanical-Toy Bowler Andy Cranes, of which the following is a specification.

This invention relates to mechanical toys, and particularly automatic toys of the gravity operated type such as described and 10 claimed in my prior Patents No. 1,151,919, August 31, 1915, No. 1,192,031, July 25, 1916 and No. 1,244,456, October 30, 1917, in which the toy simulates the action of a 15 crane or derrick for transferring material or objects from one place or position and discharging the same in another place or position.

The object of the present invention is to 20 improve the type of toys of the aforesaid mentioned patents in order to simplify the same, make its operation more positive and also to adapt the same to carry large ponderous bodies such as marbles, and in which 25 the knock-down construction is secured by a novel construction and arrangement of parts.

The invention comprises the construction and arrangement of parts hereinafter described and claimed.

In the accompanying drawings Figure 1 is a side elevation of the toy, partly in vertical section, showing the load receiving receptacle in loading position; Fig. 2 is a 35 similar view of a portion of the toy showing the load receiving receptacle in load discharging position; Fig. 3 is a plan view of the toy; Fig. 4 is a transverse section on the line 4—4, Fig. 1; and Fig. 5 is a section 40 on the line 5—5, Fig. 2.

The toy comprises a base 1, which is shown in the form of a shallow tray provided with upwardly extending flanges 2, which have holes therein to receive projections on the 45 lower ends of the supports for the operating mechanism. As shown the toy is arranged to be operated by and to carry solid ponderous bodies such as marbles 10, and the receptacle or reservoir 3 is shown in the 50 form of a trough supporting a series of marbles in line with each other, and being slightly inclined and provided at its lower end with a discharging orifice 4, which is controlled by a suitable gate or valve 5. 55 The support for the receptacle or reservoir

3 is formed by two pairs of uprights or legs 6 and 7 pivotally connected intermediate their ends by the cross bar 8 and having their ends provided with right angle projections 9, those at the lower ends of the uprights engaging in holes in the side flanges 2 of the base, and those at the upper ends of the uprights engaging in holes in the receptacle or reservoir 3. These uprights are made of resilient metal so that their ends 60 can be engaged with and disengaged from the base and receptacle by merely springing their ends laterally, and when disengaged said uprights will pivot around pivot 8 to lie in the same plane, and be in compact 65 assembly for packing.

The load carrying means comprises an arm 12 forming in effect a crane boom and carrying at one end a suitable load carrying receptacle or bucket 13, and at its opposite end a counter-weight 14. The arm 12 is shown as formed of two strips of metal having their ends in contact and secured respectively to the receptacle 13 and counter-weight 14, and intermediate their ends being spread apart and secured to a loop shaped member 15 whose upper and lower portions are provided with holes fitting a shaft 16, which is held in inclined position by a support comprising a pair of legs 17 70 formed of a continuous strip of metal bent to U-form, and a pair of braces 18 pivoted to legs 17 and 19. The lower ends of the legs 17 and braces 18 are bent outwardly at right angles and engage respectively in 75 holes 20 and 21 in the side flanges 2 of the base. The legs 17 are cross connected below their upper ends by a member 22 which is secured by the same rivets which form the pivots 19 for the braces. Said cross 80 member and the top member 23 of the U-shaped legs are provided with holes to receive the shaft 16. This shaft at its lower end is made non-circular, such as crescent shaped, as shown in Fig. 5, and the hole in 85 the cross member 22 is made of a corresponding shape, so that said shaft can be inserted in said hole in only one position and when inserted in said holes is held 90 against rotation. The loop member 15, however, is free to oscillate on said shaft.

The gate or valve 5 will be of such construction as to feed the particular form of material to be used in the toy. For solid bodies, such as marbles, said gate is shown 95

as formed of strap metal in the form of a rectangular loop and is pivoted on the longitudinal shaft 25 supported in ears 26 struck up from the metal forming the top 5 at the lower end of the receptacle or reservoir 3. The inner end 27 of this loop projects down into the trough or receptacle 3 to act as one member of an escapement to hold back the marbles 10, and its opposite 10 end 28 is bent to lie underneath the discharge opening 4, and support one of the marbles against dropping out of the trough or receptacle 3, and is then reversely bent to provide an arm 29 to be contacted by 15 the load carrying receptacle 13. An arm 11 projects laterally from the upper part of the gate 5 and serves as a counter-weight to restore the gate to normal position. When this load carrying receptacle crowds the 20 gate toward one side the marble supported by the member 28 is permitted to drop into the load carrying receptacle 13, but when the load carrying receptacle swings out of the way the gate will again swing to normal 25 position to bring the said member in such position as to support the next marble which rolls down onto it.

The load carrying receptacle 13 is shown as formed of a loop of sheet metal, riveted 30 or otherwise secured to the end of the crane boom and open at its bottom. This receptacle however will be varied according to the character of material to be handled, and it will be provided with any suitable form 35 of valve mechanism to retain the material forming the load. For a solid ponderous body as shown the valve is shown as the end of a rod or wire 30 which has a sliding movement through a hole in the side wall of 40 said receptacle, and whose opposite end is connected to a crank 31 on the upper end of the shaft 16. This crank is in such position that when the boom is in load receiving position the rod 30 is projected into the receptacle 13 so as to support the marble 45 therein, but since the shaft 16 is non-rotatable, when the boom swings to load discharging position as shown in Fig. 2, said rod is retracted sufficiently to permit the 50 marble to drop out of said receptacle. A stop 32 on the top member 23 of the legs 17 is arranged to be contacted by an arm 33 on the loop member 15 to limit the extent 55 of downwardly swinging movement of the arm 12 and cause said arm to rebound to loading position.

In order to confine the marbles discharged by the toy, I provide a suitable loop member 34 also of resilient band metal whose 60 ends are provided with inwardly projecting portions 35 engaging holes in the side flanges 2 of the base 1, so that said member 34 can be readily detached for packing. To permit the member to pack in small compass it is formed of two members pivotally 65

connected at 37 so that when detached from the base one member is folded into the other, as will be obvious.

The operation of the toy is as follows:

The marbles 10 are placed in the receptacle or reservoir 3, and roll down to the lower end of said receptacle, the foremost of said marbles coming to rest upon and being supported by the horizontal arm 28 of the gate 5. Arm 12 is then caused to 70 contact the gate with sufficient force to crowd the member 28 to one side, thus permitting the foremost marble to drop down into the load carrying receptacle 13, the arm 27 of the gate in the meantime holding back 75 the next marble. Since the arm 12 is supported on an inclined axis the weight of the marble in the receptacle 3 causes the arm 12 to swing around the inclined shaft 16, thus carrying the marble in a swinging 80 movement sidewise and downwardly. During this swinging movement the rod 30 is gradually retracted and by the time said arm approaches the limit of its downward 85 movement this rod has been retracted sufficiently to permit the marble to fall out, whereupon the counter-weight 14 swings the arm in the reverse direction, and brings the receptacle 13 against the gate 5 with sufficient impact to again crowd the gate to 90 one side and permit another marble to drop into the receptacle 13,—whereupon the foregoing movement is repeated.

The device will remain in operation as long as marbles are supplied to the receptacle 3. Its action is entirely automatic. Because of the absence of gears, pulleys or the like the mechanism is very simple and therefore positive in its action and not likely to get out of order or stick. The 100 movement in one direction is produced by the marble which will be of greater weight than that of the counter-weight 14, and the movement in the reverse direction is affected by the counter-weight.

The toy can be readily disassembled and packed in a very small space. The arm 12 is removed by merely lifting the shaft 16 out of the holes in the cross members of the legs 17. The legs 17 and braces 18 are 110 disassembled from the base by springing their lower ends inwardly and when removed the braces 18 will fold parallel to the legs 17. The trough or receptacle 3 is removed by springing the upper ends of the 120 legs 6 and 7 apart, and said legs are disengaged from the base by springing their lower ends toward each other, and when removed said legs can be folded into parallelism with each other. Likewise the retaining loop 34 is disengaged from the base by merely springing its end outwardly and thereafter the two sections of the loop are folded together on their pivot 37. Consequently all of the parts are in a practically 130

flat form, and will pack in a small carton. They can be readily assembled, as will be obvious.

Various changes can be made in the form and arrangement of the parts illustrated. The toy can be made to operate not only by means of marbles, but also by other ponderous materials, such, for instance, as sand. In the latter case the form of the storage receptacle and of the load carrying receptacle will be varied, and the valves or gates for these parts will be made of a form to retain the sand, in a manner well understood in the art.

15 I claim:

1. A mechanical toy comprising a supply receptacle, a frame carrying a load receiving receptacle and arranged to have a swinging and rising and falling movement around a non-vertical axis, means for retaining a load in said load carrying receptacle and releasing the same therefrom when in its lower position, and means for returning the load carrying receptacle to its higher position to receive another load from said storage receptacle.

2. A mechanical toy comprising a supply receptacle, a frame carrying a load receiving receptacle and arranged to have a swinging and rising and falling movement around a non-vertical axis, means for retaining a load in said load carrying receptacle and releasing the same therefrom when in its lower position, and a counter-weight for automatically returning the load receiving receptacle to its higher position to receive another load from the storage receptacle.

3. A mechanical toy comprising a supply receptacle, a frame carrying a load receiving receptacle and pivoted on an inclined axis whereby the load causes said arm to swing outwardly and downwardly, means for retaining a load in said carrying receptacle and releasing the same therefrom when in its lower position, and means for returning said carrying receptacle to its higher position to receive another load.

4. A mechanical toy comprising a supply receptacle, a frame carrying a load receiving receptacle and pivoted on an inclined axis whereby the load causes said arm to swing outwardly and downwardly, means for retaining a load in said carrying receptacle and releasing the same therefrom when in its lower position, and a counter-weight for returning said carrying receptacle to its higher position to receive another load.

5. A mechanical toy comprising a supply receptacle, a load carrying receptacle having a swinging movement around a non-vertical axis, means for depositing a load in said carrying receptacle from said storage receptacle, thereby causing the carrying

receptacle to swing away from the supply receptacle by gravity, means for retaining the contents of said carrying receptacle and releasing the same therefrom at a point removed from the supply receptacle, and a counter-weight for returning said carrying receptacle to loading position.

6. A mechanical toy comprising a supply receptacle, a load carrying receptacle mounted to have a swinging movement around an inclined axis, means for depositing a load in said carrying receptacle from said supply receptacle, thereby causing the carrying receptacle to swing away from the supply receptacle by gravity, means for retaining the load in said carrying receptacle at a point removed from said storage receptacle, and a counter-weight for returning the said carrying receptacle and releasing the same therefrom to loading position.

7. A mechanical toy comprising a supply receptacle, a frame mounted to swing around an inclined axis and provided at one end with a carrying receptacle and on its opposite end with a counter-weight, means for depositing a load in said carrying receptacle from said supply receptacle and thereby cause the frame to swing by gravity away from the supply receptacle, and means for retaining the load in said carrying receptacle and releasing the same therefrom at a point removed from said supply receptacle and thereby permit the counter-weight to return said carrying receptacle to loading position.

8. A mechanical toy comprising a supply receptacle, a frame mounted to swing around an inclined axis and provided at one end with a carrying receptacle and on its opposite end with a counter-weight, means for depositing a load in said carrying receptacle from said supply receptacle and thereby cause the frame to swing by gravity away from the supply receptacle, and means for releasing the load from said carrying receptacle, said means including a rod pivoted to a fixed point eccentric to the axis of said swinging frame.

9. A mechanical toy comprising a base, a supply receptacle, a support therefor, a swinging frame carrying a receptacle arranged to receive a load from the supply receptacle, carry said load to and deposit it at a distance, and a support for the supply receptacle comprising two pairs of legs pivotally connected intermediate their ends and having their ends formed to engage holes in the base and receptacle respectively.

10. A mechanical toy comprising a base, a supply receptacle, a support therefor, a swinging frame carrying a receptacle arranged to receive a load from the supply receptacle, carry said load to and deposit it at a distance, and a support for said load carrying frame comprising a pair of legs

and a pair of braces pivotally connected thereto, having their lower ends formed to engage holes in the base.

11. A mechanical toy comprising a base, 5 a supply receptacle, a support therefor, a swinging frame carrying a receptacle arranged to receive a load from the supply receptacle, carry said load to and deposit it at a distance, and a support for said load carrying frame comprising foldable legs and braces with a pair of cross members and having their lower ends formed to engage holes in the base, and a shaft around which the swinging frame pivots, said shaft removably and non-rotatably engaging in holes in the cross members of said legs.
12. A mechanical toy comprising a supply receptacle, a support, a shaft removably and non-rotatably held in said support in inclined position, a swinging frame mounted 15 on said shaft and carrying a receptacle ar-
- 10
- 15
- 20

ranged to receive a load from the supply receptacle, a valve for releasing the load from said carrying receptacle, an operating rod therefor, and a fixed projection from 25 said shaft pivotally connected with said operating rod, whereby the swinging of said frame on said shaft operates said valve.

13. A mechanical toy comprising a base, 30 a supply receptacle, a load carrying receptacle mounted to receive a load from said supply receptacle and carrying it to and depositing it at a distance from said supply receptacle, and a load retaining member comprising a loop formed of two members 35 pivotally connected to and foldable on each other and detachably attached to said base.

In testimony whereof I have hereunto set my hand.

BENJAMIN F. BAIN.
